UNITED STATES PATENT OFFICE.

MARY S. KJELLSTROM, OF NEW YORK, N. Y.

DESIGN FOR A FABRIC-RENOVATOR.

SPECIFICATION forming part of Design No. 23,711, dated October 23, 1894.

Application filed September 18, 1894. Serial No. 523,419. Term of patent 7 years.

To all whom it may concern:

Be it known that I, MARY S. KJELLSTROM, of New York city, in the county of New York and State of New York, have invented and produced a new and original Design for a Fabric-Renovator, of which the following is a specification.

Reference is to be had to the accompanying drawings, forming a part of this specification, in which—

Figure 1 is a perspective view of a renovator showing my design; and Fig. 2 is a sectional plan view of the same on the line 2—2 of Fig. 1.

The leading feature of my design consists

in the conical tube like figure A partly open at its side from the apex downward to a point B and connecting at the open edges with parallel plates C made in the shape of triangles having their bases extending on top in an approximately horizontal position and their outer projecting sides united as at D, as plainly illustrated in the drawings.

I claim—

The design for a renovator as herein shown and described.

MARY S. KJELLSTROM.
